(57) **CLAIM**

I claim the ornamental design for an extendable automatic tire wrench, as shown and described.

DESCRIPTION

FIG. 1 is a top perspective view of the extendable automatic tire wrench showing my new design.

FIG. 2 is a bottom perspective view.

FIG. 3 is a top perspective view of the automatic tire wrench with the handle extended.

FIG. 4 is a bottom perspective view with the handle extended.

FIG. 5 is a right side view thereof.

FIG. 6 is a left side view thereof.

FIG. 7 is a top view thereof.

FIG. 8 is a bottom view thereof.

FIG. 9 is a back view thereof; and,

FIG. 10 is a front view thereof.

1 Claim, 7 Drawing Sheets

FIG. 1

FIG. 2

FIG. 3
